DESIGN FOR A FRENCH-WINDOW CATCH.

Specification forming part of Design No. 5,501, dated January 30, 1872.

To all whom it may concern:

Be it known that I, OTTO F. FOGELSTRAND, of Kensington, in the county of Hartford and State of Connecticut, have invented and produced a new and original Design for a French-Window Catch of which the following is a specification:

The nature of my design is fully represented in the accompanying engraving, to which reference is made.

A represents the latch proper, and B its catch. The contour of each of said parts is rectangular, that of A being nearly square.

The fronts of these parts are bordered by a ledge, a. At each corner of A is a screw-hole, b, between which screw-holes, upon the upper and lower sides, is a small raised ornamental figure, c. The central front of the catch B has a like figure. The face of the knob C is ornamented by raised work, as shown.

I claim as my invention—

The design for a window-catch, as shown.
OTTO F. FOGELSTRAND.
